UNITED STATES PATENT OFFICE

105,026

DESIGN FOR A BOTTLE OR SIMILAR CONTAINER

Rollin A. Mills, Zanesville, Ohio, assignor to Maison Joubert, Inc., New York, N. Y., a corporation of New York

Application May 5, 1937, Serial No. 69,174

Term of patent 14 years

To all whom it may concern:

Be it known that I, Rollin A. Mills, a citizen of the United States of America, residing at Zanesville, county of Muskingum and State of Ohio, have invented a new, original, and ornamental Design for a Bottle or Similar Container, of which the following is a specification, reference being had to the accompanying drawing, forming a part thereof, in which

I claim:

The ornamental design for a bottle or similar container as shown.

ROLLIN A. MILLS.
